UNITED STATES PATENT OFFICE.

GASTON A. GUYOT AND ARTHUR F. GUYOT, OF ATTLEBORO, MASSACHUSETTS.

WATCH-BRACELET HOOK.

Application filed January 16, 1922. Serial No. 529,424.

To all whom it may concern:

Be it known that we, GASTON A. GUYOT and ARTHUR F. GUYOT, citizens of the United States, residing at Attleboro, in the county of Bristol and State of Massachusetts, have invented certain new and useful Improvements in a Watch-Bracelet Hook, of which the following is a specification.

10 This invention relates to improvements in the construction of hooks or clasps more particularly adapted for use in releasably connecting the ends of a bracelet to the opposite sides of a wrist watch, and the object of this invention is to provide such a hook having a body portion which comprises front and back members connected by a pair of widely-separated joint portions which are folded so as to engage and 20 support each other a substantial distance inward from the bend whereby the constant opening and closing of the hook will not tend to weaken the stock at the fold, the free end of one of the members being provided with a hook which is closed by tension of the opposite member resting against its end.

With these and other objects in view, the invention consists of certain novel features 30 of construction, as will be more fully described, and particularly pointed out in the appended claims.

In the accompanying drawings,

Figure 1 is an edge view of a watch showing our improved strap-hook as attached thereto.

Figure 2 is a front view of our improved hook showing the spaced apart portions which connect the front and back members 40 of the hook.

Figure 3 is a back view of the hook showing the slot through which the strap is passed.

Figure 4 is a sectional edge view of the 45 hook illustrating the strap in dotted lines as passing through openings in both the front and back members of the hook; also showing the hook member as being provided with an open loop at the fold and the parts supporting each other a substantial distance inward from the fold.

Figure 5 is a modification illustrating the 50 back and front members of the hook as closed upon itself at the fold for a substan-

tial distance inward from the extremity of 55 the fold.

It is found in practice that where a hook or other member formed of a single piece of sheet metal is folded upon itself in an open fold that the constant working of the 60 parts soon crystallizes the metal at the fold causing it to break at this point, and the following is a detailed description of one construction of hook member which will prevent the bending of the stock at the 65 fold each time the hook members are operated and so prevent breakage at this point and consequently greatly extending the operating life of the device.

With reference to the drawings, 10 designates the front plate of the hook and 11 the back plate thereof both of which are connected together and are formed of a single piece of sheet stock folded upon itself. The middle portion of the stock at 75 the fold is cut away as at 12 providing a pair of widely-separated portions 13 connecting the front and back members. These joint portions are preferably folded into an open loop shaped as illustrated at 14 80 in Figure 4 and the sides of the front and back members are turned inwardly to engage each other at 15 at a point a substantial distance inward from the extremity 16 of the bend.

The upper or free end of the back plate is 85 provided with a tongue 17 which is bent over into hook form to lay against the outside surface of the projection 18 on the front plate 10.

Both the front and back plates are provided with registering openings 19 through 90 which a strap or ribbon 20 of the bracelet or band may pass.

In some instances instead of folding the 95 stock at the bend into loop form as illustrated in Figure 4, we fold this stock back upon itself as at 21 in Figure 5, whereby it is caused to support itself for a substantial distance inwardly from the extremity of 100 the fold.

By our improved construction of hook member which is provided with widely-spaced apart joint portions folded so that the front and back portions will engage and support each other a substantial distance inward from the bend, the stock at the fold is prevented from being bent each time the hook 105

is opened and closed thereby greatly increasing the wearing life of the hook and giving greater resiliency to its action.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. A watch bracelet hook formed of a single piece of stock comprising front and back body members connected by a pair of widely-separated joint portions folded to engage and support each other a substantial distance inward from the bend, a yieldable tongue on the free end of one of said members bent into hook form and the opposite member being adapted to close said hook by

the inherent spring at the joint, said members being provided with a strap-receiving opening.

2. A watch bracelet hook formed of a single piece of folded stock comprising front and back body members connected by widely-separated resilient joint portions folded into open loop form, each being shaped to engage and support each other at a point a substantial distance inward from the bend, a yieldable tongue on the free end of one of said members bent into hook form and the opposite member being adapted to close said hook by the inherent spring at the joint, both of said members being provided with registering strap-receiving openings.

In testimony whereof we affix our signatures.

GASTON A. GUYOT.
ARTHUR F. GUYOT.
